POPPET VALVE AND GUIDE ASSEMBLY

Walter D. Appel, Orchard Lake, Mich., assignor
to General Motors Corporation, Detroit, Mich.,
a corporation of Delaware

Application September 16, 1944, Serial No. 554,355

3 Claims. (Cl. 123—188)

1

The use of high octane leaded fuel in internal combustion engines has created a problem which this invention aims to solve. The problem arises from the very considerable deposits of lead products on and in the vicinity of the exhaust poppet valves. These valves are opened positively by cam action but close under the influence of springs. The deposit frequently causes the valve stems to become so stuck in the valve guides that the springs cannot overcome the resistance and close the valves. Thereupon the combustion chamber gases pass around the valve heads, burn the heads and stems and soon the valves must be replaced. In the case of lower octane fuels similar but less serious sticking occurs and in such cases the difficulty has been to some extent lessened by the use of counterbored guides or reduced valve stem diameters within the ends of the guides.

The present invention has taken cognizance of these prior expedients adopted to overcome the effects of carbon deposits from relatively low octane fuels but it has been found that a mere unscientifically counterbored guide or a two diameter stem is not enough to solve the present problem.

Very briefly stated, the problem has been solved by resort to a two dimension valve stem movable in a valve guide having a bore of uniform diameter, the parts being so dimensioned relative to the position of the valve head and its seat and the stroke of the cam that the shoulder between the parts of the stem shall always be within the guide and shall approach but not reach the end of the guide as the valve opens. The best results also require that the radial dimension of the annular space between the reduced dimension part of the stem and the wall of the guide shall be such as to permit the collection of a moderate coating of lead deposit on the stem but that it shall not be so large as to permit a turbulence of gas within the space and consequently the carrying of much of the lead deposit into this chamber. The axial dimension should not be extended unduly else the stem will not be properly guided and the valve will not seat as it should.

The structure which is believed to be the best to carry out the inventive idea is shown on the accompanying drawing, in which:

Fig. 1 is a view in elevation of a conventional valve assembly.

Figs. 2 and 3 are similar views of my new assembly with the valve in two different positions.

While with certain valve dimensions good re-

2

sults may be had from the use of a counterbored guide this invention makes use of a guide with a uniform bore through which slides a two dimension stem. Among the reasons for selecting the second of these expedients are the following. The length of annular chamber is constant when one counterbores the guide whereas with the two dimension stem the guiding portion of the guide increases in length as the valve opens. Also there is no provision for removing the deposit on the inner wall of the counterbored guide. On the contrary, the shoulder between the two parts of the two dimension stem scrapes the deposit from the walls of the guide due to the positive action of the cam. There is another and very important reason for selecting the second of the two expedients. The hot gases from around the valve head build up deposits along the stem. Near the head the more intense heat burns these to a kind of film but a little way down the stem, where the heat is somewhat less, there is found a bulbous deposit of some appreciable size. This bulbous deposit, if it gets within the counterbore of a guide necessitates an otherwise needlessly large counterbore to prevent sticking. With a reduced dimensioned stem having less heat conducting metal the critically hot region is nearer the valve head and hence the bulbous region at the lower end of the critically hot region is further from the end of the guide. Since it is nearer the head it is well above the end of the guide and does not cause sticking because of contact with the guide. A deposit does collect on the end of the guide, and just within the end. Therefore the shoulder which is within the guide should be so located that, in valve position, it will not contact this deposit. As a matter of fact the deposit at the guide opening is of use in that it partly closes the annular space within the guide and around the stem thus sealing off this space to such an extent as to prevent the lead deposits being carried into the space by the turbulent gases outside. There are therefore many reasons for reducing the stem diameter rather than counterboring the guide. The experiments have shown that very good results are obtained with a valve having a 13-32 inch stem reduced to 11-32 inch from the valve head for a distance of about 1 $\frac{1}{8}$ in. the shoulder being always in the guide and the movement being such that, when the valve is opened by the cam, the shoulder shall be about $\frac{1}{8}$ in. from the end of the guide. This will avoid the danger of the large diameter part sticking to the deposit just within the guide opening. If, too, the radial

dimension of the annular space is between $\frac{1}{32}$ and $\frac{3}{64}$ in., the space has been found to be sufficient to accommodate the slight collection of deposit on the stem which will occur in spite of the nearly closed annular space. As explained above, any deposit on the inner wall of the guide except that adjacent the opening beyond the limit of outward movement of the shoulder on the stem is scraped off by the shoulder.

It is believed that the invention will be understood from the description above. The drawing serves to illustrate it. On the drawing, the old type of valve assembly is shown by Fig. 1. Here the valve guide 5 has a uniform bore and the valve stem 7 is also of uniform diameter. The valve head 9 is shown seated. As explained above, the tendency to collect a deposit on the stem adjacent the end of the guide is indicated by a bulbous formation marked 11 (exaggerated). It will be readily seen that the deposit may cause the valve to stick at the end of the guide so that the releasing spring may be unable to break it away. Fig. 2 shows the same valve guide 5 but my improved valve with its stem 7' reduced in diameter as at 13 from the head to a point marked a which is well within the guide when the valve is seated. Also the reduced diameter of the valve stem 7' has caused the bulb 11' to form further from the end of the guide than before, so that it cannot cause sticking. The shoulder at a moves from the position shown by

Fig. 2 toward the open end of the guide and scrapes off any deposit which may form on the wall of the guide. However, as shown by Fig. 3, when the valve reaches its open position the shoulder is still a little way from the end of the guide and does not engage and stick to the deposit 15 which forms at the end of and extends just a little way into the guide. It will also be seen that this deposit 15 partially closes the annular chamber at the end of the guide so that the turbulence outside may not extend thereinto and carry an undue quantity of carbon or lead products into the chamber.

I claim:

1. A valve and guide assembly, said valve having an integral stem with parts of two different diameters forming a shoulder therebetween, the parts being so proportioned that the shoulder is always within the guide and that the shoulder approaches but does not reach the end of the guide on the valve opening movement.
2. The invention defined by claim 1, the difference in diameter being such as to permit only a slight deposit within the space around the stem within the guide.
3. The invention defined by claim 1, the opening movement of the valve carrying the shoulder to a limit at about one-eighth of an inch from the end of the guide.
